(57) **CLAIM**

The ornamental design for a sun shield having a top panel and a pair of side panels, as shown and described.

DESCRIPTION

FIG. 1 is a plane view of a sun shield having a top panel and a pair of side panels showing my novel and non-obvious design, where the top panel is in a straight position and the pair of side panels is in a bended position.

FIG. 2 is a plane view thereof with the top panel of my sun shield in an inclined position and with side panels in a bended position.

FIG. 3 is a plane view thereof with the top panel and the side panels of my sun shield in a straight position.

FIG. 4 is a top elevational view thereof with the top panel and the side panels of my sun shield in an inclined position.

FIG. 5 is a plane view thereof.

FIG. 6 is a top elevational view thereof with the top panel of my sun shield extended in a straight position.

FIG. 7 is a front view thereof with the top panel of my sun shield extended in a straight position.

FIG. 8 is a side view thereof with the side panel of my sun shield extended in a straight position.

FIG. 9 is a top elevational view thereof with the top panel of my sun shield extended in an inclined position.

FIG. 10 is a front view thereof with the top panel of my sun shield extended in an inclined position.

FIG. 11 is a rear view thereof with the top panel of my sun shield extended in a inclined position; and,

FIG. 12 is a side view thereof with the side panel of my sun shield extended in an inclined position.

Any broken lines the figures are included for the purpose of illustrating a sunglasses and/or other glasses that form no part of the claimed design.
